UNITED STATES PATENT OFFICE.

ELIZABETH M. SHEERAN, OF ALAMEDA, CALIFORNIA.

SCORE-CARD FOR GAMES.

No. 884,221.

Specification of Letters Patent.

Patented April 7, 1908.

Application filed May 17, 1907. Serial No. 374,212.

To all whom it may concern:

Be it known that I, ELIZABETH M. SHEERAN, a citizen of the United States of America, and a resident of Alameda, in the county of 5 Alameda and State of California, have invented new and useful Improvements in Score-Cards for Games, of which the following is a specification.

This invention relates to an improved 10 score-card for games played with cards, and it consists in a tablet or card having a plurality of record-spaces of different numerical values arranged around the sides and ends of the card, and a middle record-space separating 15 the marginal record-spaces on one side from those on the other, the said middle record-space being common to all the marginal record-spaces, all as hereinafter fully described and set forth in the claims at the 20 end of this specification.

The object of my invention is to provide an improved score-card for games played with cards, and particularly for keeping a record of the gains and losses in the game of "500".

25 The score-card of my invention has its surface divided or separated by longitudinal lines and transverse lines into marginal record-spaces and middle record-spaces which are arranged and combined substantially as 30 I have illustrated in the accompanying drawing in which the figure represents the face of a record-card for use in keeping the score of both gains and losses in games, such as the game of "500".

35 The transverse band *a*, divides the face of the card A into two sections *b*—*c*, of which one is designed to keep a record of the gains, and the other section a record of the losses. Usually the portion or section *b* appropriated

40 for the records of the gains is of larger area than the other section *c*. Each of these sections is divided by lines *d*—*e*, *d*¹—*e*¹ running longitudinally of the card, and also substantially parallel with its sides, into 45 three zones or strips, as seen at *f*—*g*—*h*; on one side of the band *a*, and at *f*¹—*g*¹—*h*¹ on the opposite side. By transverse lines extending from the lines *d*—*e*, *d*¹—*e*¹, the zones or portions of the face included between those lines and the outer edges are divided into the record-spaces *k*—*k*¹—*k*², on one side, and similar spaces *m*—*m*¹—*m*², on the opposite side of the band *a*.

50 The spaces produced by dividing the face of the card in this manner are provided with distinguishing marks or numbers to indicate

the numerical value of the record-marks made in them during the game. The spaces, also, are arranged, as shown, for the purpose of readily inserting the card at any given record-space between the jaws of a ticket-punch, and the points are scored by that means instead of by the less permanent marking with a lead-pencil. The marginal record-spaces are of such dimensions also 60 that each space will contain a number of punch-marks or scores, so that the points in one game, or in a group of games, may be recorded on the same card, and the total number of scores contained in each marginal record-space at the end of a game, or a 65 group or series of games, can be recorded opposite each marginal record-space in the middle record-space. This last-mentioned space thus serves for reckoning and recording the 70 total number of points scored in the various marginal record-spaces, as well as for showing the sum-total both of the points gained 75 and the points lost.

The marginal record-spaces in both sets or 80 series *k*—*k*¹—*k*², *m*—*m*¹—*m*², give a fixed numerical value to the punches or scores made in each, and the value of each space is indicated by numerals printed thereon, beginning with the lowest denomination in the 85 first space in each section nearest the dividing band *a* and continuing along the side and across the end and thence up the opposite side in increasing order, according to the schedule or requirements of the game. 90

The band *a* dividing the two sections of record-spaces is utilized to display the name of the player, the number of the table, and other matter useful or convenient for identifying the score or the player for whom the 95 record is made.

What I claim as my invention, is:—

A score card having upon its face transverse lines dividing it into two sections, and having a transverse record space between 100 said lines for the insertion of printed matter, each section being divided by longitudinal lines to form a central blank space and by transverse lines to form with said longitudinal lines record spaces, the record spaces in 105 one section being used for the recording of gains and in the other section for the recording of losses.

ELIZABETH M. SHEERAN.
